J. A. PETRIE.
ELECTRIC HAND MIRROR.
APPLICATION FILED JAN. 7, 1916.

1,216,724.

Patented Feb. 20, 1917.

UNITED STATES PATENT OFFICE.

JOHN A. PETRIE, OF NEW HAVEN, CONNECTICUT.

ELECTRIC HAND-MIRROR.

1,216,724.

Specification of Letters Patent. Patented Feb. 20, 1917.

Application filed January 7, 1916. Serial No. 70,773.

To all whom it may concern:

Be it known that I, JOHN A. PETRIE, a citizen of the United States, residing at New Haven, in the county of New Haven and State of Connecticut, have invented a new and useful Improvement in Electric Hand-Mirrors; and I do hereby declare the following, when taken in connection with the accompanying drawings and the characters of reference marked thereon, to be a full, clear, and exact description of the same, and which said drawings constitute part of this application, and represent, in—

Figure 1 a view in front elevation of one form which my improved electric hand-mirror may assume.

Fig. 2 a view thereof in vertical central section.

Fig. 3 a view thereof in transverse section on the line *a*—*b* of Fig. 1, looking downward.

My invention relates to an improvement in electric hand-mirrors, the object being to provide a simple and convenient mirror of superior efficiency.

With these ends in view, my invention consists in an electric hand-mirror having certain details of construction as will be hereinafter described and pointed out in the claims.

In carrying out my invention as herein shown, I employ a circular mirror-plate 2 the beveled edge of which is inserted into a tube-like binding-ring 3 which in turn is set into the open front of a circular, shallow, cup-like mirror back 4 provided with a tubular handle 5 the upper end of which is cut away in front to form a deep recess 6 adjacent to the center of the lower edge of the mirror-plate 2, to receive the reflector 7, the inclined bottom of which is formed with a threaded socket 8 for the reception of a small incandescent lamp bulb 9 which is slightly tilted forward from the vertical plane of the mirror. The mirror-back 4 is located in the plane of its tubular handle 5, and the lower edge of the mirror-plate 2 is located entirely above the upper edge of the recess 6 and the reflector 7 which latter is located so far back in the recess 6 in the front of the handle 5, as to permit the lamp to be protected against injury and to shade the mirror into which the lamp, when so located, cannot directly shine. By preference the inner face of the reflecting chamber 7

will be silvered or nickelated, or otherwise provided with a reflecting surface. Within the tubular handle 5, I locate a removable dry battery 10 furnished at its upper end with a contact 11 designed to engage with a contact 12 at the lower end of the lamp 9. The battery 10 is held in place by a removable cap 13, provided, as shown, in its upper edge with two bayonet-joint notches 14 located diametrically opposite each other and arranged to co-act with locking-lugs 15 upon the periphery of the lower end of the handle 5. The said cap 13 has threaded into its lower end a contact thumb-screw 16 having at its projecting lower end a knurled button 17, while its upper end is engaged with the bottom of the battery 10. The contact 11 of the battery is normally held away from the contact 12 of the lamp by means of a helical spring 18 interposed between the upper end of the battery and the inclined bottom of the reflector 7.

To close the circuit, the screw 16 is turned by its knurled button 17 so as to overcome the tension of the spring 18 and permit the points 11 and 12 to be brought into engagement, whereby the current of the battery 10 is sent through the lamp 9. By reversing the screw 16, the spring 18 is allowed to assert itself and break the contact between the points 11 and 12, thus extinguishing the lamp.

Under my construction, the lamp is placed so that none of its rays are thrown directly upon the mirror itself, but rather upon the face or hair, and from thence reflected into the mirror, thus securing a far better diffusion of light and a clearer image than can be secured by arranging the lamp so as to throw the rays of light directly upon the mirror-plate itself.

I claim:—

1. In an electric hand mirror, the combination with a mirror-back having a tubular handle located in line with it and formed in the front face of its upper end with a recess, of a mirror-plate mounted in the said mirror-back, in which it is positioned with its lower edge entirely above the said recess, an incandescent electric lamp located in the said recess, a reflecting surface located back of the said lamp, a removable battery located in the said tubular handle, and means for closing a circuit through the said lamp and battery, the said lamp being positioned

in the recess so as to be protected and so that its rays will not shine directly into the said mirror.

2. In an electric hand-mirror, the combination with a mirror-back having a tubular handle located in line with it and formed in the front face of its upper end with a recess, of a mirror-plate mounted in the said mirror-back in which it is positioned with its lower edge entirely above the said recess,

a reflector located in the said recess, an incandescent lamp located in the said recess in which it is tilted forward, a battery in the said handle, and means for closing the circuit through the said lamp and battery, the 15 said lamp being positioned in the said recess so as to be protected and so that its rays will not shine directly into the said mirror.

JOHN A. PETRIE.
